CLAIM

The ornamental design for a headlamp, as shown and described.

DESCRIPTION

FIG. 1 is a front, left-side, top perspective view of the headlamp;

FIG. 2 is a front, right-side, top perspective view thereof;

FIG. 3 is a front elevational view thereof;

FIG. 4 is a top plan view thereof;

FIG. 5 is a right-side elevational view thereof;

FIG. 6 is a left-side elevational view thereof;

FIG. 7 is a rear elevational view thereof; and,

FIG. 8 is a bottom plan view thereof.

The broken lines depict unclaimed parts of the headlamp, and thus form no part of the claimed design.

1 Claim, 6 Drawing Sheets
